UNITED STATES PATENT OFFICE.

GEORGE H. LOBER, OF TOLEDO, OHIO.

RADIATOR.

Application filed August 25, 1922. Serial No. 584,175.

To all whom it may concern:

Be it known that I, GEORGE H. LOBER, a citizen of the United States, and a resident of Toledo, in the county of Lucas and State of Ohio, have made an invention appertaining to Radiators; and I do hereby declare the following to be a full, clear, and exact description of the invention, such as will enable others skilled in the art to which it applies to make and use the same, reference being had to the accompanying drawings, and to the characters of reference marked thereon, which form a part of this specification.

My invention has for its object to provide a radiator for internal combustion engines, particularly for automobile engines, wherein the core is so constructed that the water passageways will readily expand in case the water used as a cooling medium freezes, and will contract or return to its normal position when the ice formed from the water melts. Thus the passageways will be maintained normally in such a condition that they will expand on the freezing of the water in the radiator. The expansibility of the walls of the passageways thus prevents tearing of the edges of the sheet material of which they are commonly formed. The invention also has for its object to provide in connection with such a radiator cooling means formed of metal strips that are in contact with the walls of the passageways and which are so constructed that the strips forming the walls of the passageways and the cooling strips may be readily assembled and so as to form air passageways located between the cooling strips and the walls of the water passageways, forming at the same time the conventional honey-comb faces of the core at the edges of the strips. A particular advantage is the racking or stacking of the strips in the formation of the core preparatory to the usual dipping or soldering process in the formation of the radiator core. By my invention the angular corrugated walls of the passageways are readily placed in the exact and proper position relative to each other and so as to place the walls of each water passageway in proper position to form and maintain, after the core is assembled, an open passageway for the water. Inasmuch as the cooling strips are so constructed as to maintain the angular corrugations of the walls of the water passageways in position after the core is formed,

and while in use in the radiator, and by reason of the fact that the core is so constructed that the water passageways may expand during freezing of the water in the radiator, the strips that form the core may be made of very much thinner metal, and also of spring metal unannealed, which greatly reduces the cost of the radiator.

The invention may be used in connection with radiators of different forms. To illustrate a practical application of the invention I have shown in the drawings a core containing the invention as an example of structures containing the invention and shall describe it hereinafter.

Figure 1 of the drawings illustrates a front view of the conventional radiator. Fig. 2 illustrates a front view and a sectional view of a part of the core. The sectional view is that shown above the line 2—2. Fig. 3 is a perspective view of a racking or cooling strip that separates the walls of the water passageways in the core of the radiator. Fig. 4 illustrates a modification of the structure illustrated in Fig. 2, showing a side view of a part of the core below the line 4—4 and a sectional view of the core above the line 4—4.

In Figure 2, 1 is the core that connects the upper and lower water chambers of the radiator in the manner well known in the art. The core is provided with a plurality of water passageways that extend from the top of the radiator to the bottom of the radiator and connect together the water chambers of the radiator. In the form of construction illustrated in Fig. 2 the water passageways 2 are formed of angular corrugated walls, the angles 3 between the portions 4 that form the corrugations being located substantially in parallel lines and the walls being slightly spaced apart to form narrow passageways for the water. Each of the portions of the walls between the angles or corners formed are concave, that is, they conform to parts of cylindrical surfaces having substantially horizontal axes extending at right angles to the faces of the core of the radiator and located on opposite sides of the passageway. In thus conforming to the surfaces of cylinders the metals that form portions of opposite sides of each passageway are located nearer together substantially at horizontal lines extending along the central parts of the portions and at right angles to the faces of the core than at the angles. When, there-

fore, the radiator freezes, that is, when the water expands during its freezing action, the bellied portions thus formed readily expand outward to near the plane form as distinct from the cylindrical, and their elasticity causes them to immediately return to their normal position when the ice melts, that is, when the radiator is "thawed out." The principle of operation is substantially that of the bottom of the oil can from which oil is ejected in spurts by pressure on the bottom of the oil can. The bottom being convex on the side where the pressure is exerted, the elasticity and the shape of the metal on the bottom causes it to return immediately.

The walls of the passageways 2 are formed of narrow strips of sheet metal and preferably of nontempered brass, and thus they are exceedingly elastic and operate to contract and conform to their original condition after expansion. The body portions of each pair of strips forming the walls of the passageway are spaced apart by offsetting edge portions of the strips by means of dies, in the manner well known in the art, the edge portions being soldered during the dipping process. The strips, moreover, are formed of comparatively thin metal, and being formed of nontempered metal, which gives the advantages described above, it is difficult, except by my invention, to position the strips of each passageway so that they will not contact somewhere along the passageways, either in the assembling or in the use of the radiator. By my invention I have provided a means whereby the passageways will not only be formed continuous, but will be maintained continuous in the use of the radiator. Also my invention enables rapid assembly of the core preparatory to the dipping of the core in order to solder all of the strips together at one and the same time. Strips 5 are located on opposite sides of each pair of strips that form the water passageways. The strips 5 are provided with raised portions 6 and 7 that extend outward from opposite sides of the body portions of the strips 5. When each of the strips 5 are in the position shown in Fig. 3 the portions 6 extend forward and the portions 7 extend rearward. Thus in looking at the strips from the side shown in the figure the portions 6 are raised, while the portions 7 are depressed.

The raised portions 6 and 7 are each defined by four sloping surfaces 8 and 9, and a notch 10 that is located at the top or outer corner of the sloping surfaces 8 and 9. The notch 10 of each of the raised portions extends across the top or outer corner of the raised portions. Since the consecutive corners of the corrugated strips that form the water passageways are located one above the other, and since the angles are located in substantially horizontal lines across the face

of the core, the raised portions that are located on opposite sides of each of the strips 5 are likewise located slightly above each other. When, therefore, the strips are assembled they are placed in horizontal positions and the strip 5 is laid on to the upper of the strips that forms a water passageway, and since the raised portions on one side of the strip 5, and particularly the notches of the said raised portions, are in position to engage the corners of the said corrugated strip that form a wall of a passageway, the raised portions of the strip 5 will rest on the said corners and at the same time the weight of the piled strips will force the corners into position in the notches 10 of the strips 5. Thus the corners of the corrugated strips will be forced into a definite position relative to each other, which will properly space the portions of the walls located between the notches with which the ends of such portions make contact. If desired, the raised portions 6 and 7 may be so located as to make contact and position the consecutive corners of the strips that form the walls of the passageways. In the construction shown, however, I have found it desirable to accurately space each third corner located on one side of each passageway. By this arrangement the strips which are elastic and consequently vary slightly in form, notwithstanding the fact that they may be produced from the same die, will be accurately positioned throughout their length, and furthermore in use, particularly as they change temperature, their relative positions will also be maintained. Furthermore, in racking or stacking the strips to form the core they may be rapidly placed and still have the notches engaging the corners and as the strips are piled one above the other they slip into position in the notches so that when they are finally all clamped together preparatory to dipping they are automatically secured in proper alignment to produce the desired space between the walls of the passageway, notwithstanding their slight variation in form.

If the raised portions of the strips 5 do not contact with all of the corners the strips 5 may be cut to form the oblong openings 11 which will permit the air to readily pass through or distribute itself throughout the parts of the radiator. The strip 5 thus forms not only a spacing strip as between the water passageways and the corners of the water passageways, but also a cooling strip which increases the area of radiation of the heat of the radiator.

The edges of the strips that form the water passageways 2, and the edges of the strips 5 are corrugated, and the corners of the corrugations of the strips 5 are in line with the notches 10 so that the corners of the corrugations of the edges of the strips

5 meet or contact with the corners of edges of the strips that form the water passageways 2, and thus a cellular appearance, each cell being in the form of a square, is given 5 to the faces of the core.

When the strips are secured together by a suitable clamping device and the edges of the strips are dipped in solder, the solder operates to seal the water passageways along 10 the edges of the strips and solder the edges of the strips that form the water passageways to the edges of the strips 5 at the corners where they contact with the corners of the corrugated edge portions of the strips 15 that form the water passageways.

In the form of the device illustrated in Fig. 4 the water passageways 12 may also be formed of angular corrugated strips 13 and 14 that have the same shape as the strips 20 that form the water passageways in the form of construction illustrated in Fig. 2, and the water passageways 15 that may be formed of flat parallel strips having the usual offset edge portions, while the strips 16 may be 25 provided with the raised portions 17 having the notches 18 that engage certain of the corners of the strips 13 and 14 and the raised portions 19 that are flat at the outer ends of the raised portions, and where they contact with the strips 20 and 21 that form the straight water passageways 15. Thus the raised portions of the spacing strips 5 and 6 may be provided with notches or may be 30 formed with contact surfaces that conform to the shape of the walls of the water passageways where they contact with the walls of the passageways. Unless they are provided with notches to space the corners of corrugated strips they form merely spacing 35 strips as between water passageways. The spacing means afforded by the raised portions of the spacing strips positions the water passageways in the same spaced relation that the corners of the corrugated edge 40 portions of the strips that form the water

passageways and the spacing strips, with the result that the walls of the water passageways are spaced from the walls of adjoining water passageways not only by the corrugations of the edge portions of the strips that 50 form the water passageways, but also by means located intermediate the said edges, thus providing a compact, well sustained radiator, and yet leaving air space for the movement of the air through the radiator. 55

By the use of the spacing strips I have provided an exceedingly efficient radiator which enables the reduction of the cost of production and at the same time decreases the cost of upkeep of the radiator, particularly as against the effect of freezing of 60 water in the radiator.

I claim:

1. In a radiator for internal combustion engines, water passageways formed of a plurality of pairs of angularly corrugated strips, the apices being located in horizontal planes, the portions between the apices of the angles of the strips being bellied arcuately inward with respect to the passageway and 65 expansible outward on freezing the water in the passageway of the radiator.

2. In a radiator for internal combustion engines, water passageways formed of a plurality of pairs of angularly corrugated 70 strips, the strips having edge spacing angular corrugations, a plurality of spacing strips located between each pair of strips that form the water passageway and having edge angular corrugations, the corners of the 75 said edges contacting with each other, the central part of the spacing strips being substantially plane and having protruding parts extending from the plane portion, the said protruding parts having notches fitting 80 the apices of the angular strips that form the water passageway.

In testimony whereof I have hereunto signed my name to this specification.

GEORGE H. LOBER.
